TYPESETTING MACHINE

Clark S. Stevens, St. Paul, Minn.

Application March 10, 1939, Serial No. 260,963

6 Claims. (Cl. 276—45)

The invention relates to typesetting machines, particularly designed for composing and distributing the type for multigraphs.

A particular object of the invention is to provide an apparatus by which type of varying thickness may be composed and distributed to a standard multigraph.

In carrying out the invention, the standard construction of typesetting bank may be employed, which as now constructed can only compose and feed type of even thickness to the multigraph printer, the type being fed into channels of the bank and from the bank fed to the multigraph by a fork.

15 In the present invention attachment means are provided in connection with the channels of the bank, permitting type of uneven thickness to be separately fed into type holding channels of the bank and improved means in connection with the standard fork to cooperate in the feeding of the separated type of varying thicknesses.

20 Improvements are further provided in connection with the delivery ends of the type holding channels of the bank to permit the removal 25 of the type of varying thicknesses.

The invention in all of its details will be more fully described in the following specification and shown in the accompanying drawings, wherein:

Figure 1 is a perspective view of the bank holding frame of a typesetter machine fitted with the improvements of the present invention.

Figure 2 is a side view of one of the type holding channels of the bank illustrated in Figure 1.

Figure 3 is a perspective view, partly broken away, of the lower portion of the bank.

Figure 4 is a perspective view of a portion of the upper end of the bank.

Figure 5 is a sectional view on line 5—5 of Figure 4.

40 Figure 6 is a perspective view of a portion of the upper end of the bank illustrating a special construction of bank adapted for use independent of the invention.

Figure 7 is a partial side view of the type holding channel and supporting framework, shown in Figure 6.

Figure 8 is a sectional view illustrating the modified form of attachment for the upper end 50 of the bank.

Figure 9 is a view of a plurality of type of varying thicknesses used in the operation of the machine.

Figure 10 is a sectional view of the end of the 55 fork for depositing the type in the bank.

Figures 11 and 12 are detail views of members of the feeding fork.

Figure 13 is a view of the end of the setting fork and its attachment; and

Figure 14 is a perspective view of the end of 5 the setting fork shown arranged in feeding connection with the channels of the type holding bank.

A represents the framework for supporting the type holding bank employed for setting up type 10 for multigraph use. A plurality of banks are slidably supported in the usual manner in the frame with inclined shelves 2 constituting the bottom rests for the banks.

Each bank is comprised of a plurality of type 15 holding channels, which channels are formed by the separated I bars 3. These I bars are inset in grooves 4 in cross members 5 and 6 supporting the lower and upper ends of the bars. In the present invention, the upper and lower ends of 20 the I bars forming the type channels at their upper and lower ends are separable from the main portion of the bars as in the following manner:

In the standard bank the bars are formed with 25 beveled upper ends 7, and as shown in Figure 4 the upper beveled ends are cut off and squared channel ends 8 are supported in a bar 9, the bar 9 being removably keyed to the bar 6, as by keys 10. The cross bar 9 is formed with a downwardly projecting portion 11 having a flange 12 for the purpose hereinafter set forth. Thus, as shown, the channel ends 8 form a continuation 30 of the main portion of the channel bars. To adapt the bank for use in handling ordinary 35 multigraph type, a plurality of standard channel bar ends 13 are supported in a cross bar 14, the cross bar 14 being connected to the main cross bar 6 by pins 15 corresponding to the pins 10, and the entire section of removable ends and 40 supporting bar 14 may be anchored in position as by a nut 16 fastening the end of the removable section to the framework.

In order to adapt the lower delivery ends of 45 the channel bars to the present invention, removable extension ends for the lower ends of the bars are provided mounted on a cross bar 16 keyed to the cross bar 5 as by pins 10'. As shown in Figure 3 these removable channel ends 17 abut against and in alignment with the main 50 portion of the channel bars and are formed with openings 18 of varying sizes to discharge different thicknesses of type. The standard abutments 18' are supported upon the bar 16 below and intermediate the lower ends of the channels 55

and the separation fingers 19 are formed on the lower ends of the channel bars which stand intermediate the abutments.

Carried upon the bar 16 below the abutments 5 18 is the standard indicating type panel 20. Where the machine is used for standard multigraph type the extension end just described is removed and replaced by an extension end of similar construction, but with beveled end channel bars and type discharge openings of uniform size.

In carrying out the present invention, as illustrated particularly in Figure 4, there is positioned over the upper ends of the squared channel bars an angle-shaped frame 21 fastened to the framework as by a bolt 22 passing through the end of the angle frame. This frame consists of a lip portion 23 overlapping the channel bars and spaced therefrom. A connecting vertical bar portion 24 is spaced from the ends of the channel bars, the lower end of the bar portion 24 terminating in a horizontally extending wall portion 25, the bottom of which wall portion 25 stands in alignment with the bottom of the type holding channels formed by the channel bars. The vertical wall portion 24 of the frame 21 is formed in its face opposite the ends of the type channels with a plurality of depressions indicated by the numeral 26 in Figure 5, these depressions being of a depth to form spaces adjacent the ends of the type holding channels corresponding to the thicknesses of different type designed for the respective channels.

In order to utilize the sorting frame 21 in connection with the bank without squaring off the upper ends of the channel bars, the means shown in Figure 8 may be employed. In this construction a cross bar 27, corresponding to the cross bar 9 but made somewhat wider, is employed to support the squared end channel bars 28, which will align with the channel bars of the bank, the inner ends of the extension bars 28 having inclined inner ends to fit against the inclined ends of the regular channel bars. The cross bar 27 will fit under the ends of the regular channel bars, as shown in Figure 8, and be keyed to the cross bar 6 as by pins 29. The sorting frame 21 in this case is preferably physically connected to the cross bar 27. Thus, the combined cross bar 27 and sorting frame 21 and supported channel ends 28 will form a unitary device that when placed in position as shown in Figure 8 will bring about an extension and squaring of the ends of the type holding channel bars, affording squared ends to the channel bars and a proper spacing of the sorting frame. As will be evident the same purpose will be accomplished as with the form shown in Figure 4.

In carrying out the present invention I provide for depositing type of varying thicknesses in the respective channels. The spacing fork construction illustrated in Figures 10 to 14 is employed. The end of the standard fork 30 is removed and a special fork head 31 secured upon the fork as by pins 32 carried by the fork and projecting into openings in the fork end. The fork and fork end are formed with the usual type holding channel 33, and the end of the channel in the fork end is formed with a large discharge opening 34 for the type.

The resting of the plunger 37 upon the flange 12 without any set pressure upon the fork head 31 permits the fork head 31 to be slid from side to side along the flange 12 for the registering of the end tongue 35 of the fork head with

its associated slot 36. When a forward pressure is placed upon the fork head it will push the plunger 37 inwardly against the spring 42 thus releasing the lifting bar from the spring 43 which tends to lift the type held atop the plate 41 so that the type face will contact the resilient insertion 45 along which the type slides under pressure until it is permitted to be forced upward into the depression 26 from whence it will slide down the channel assigned for the type.

The fork head is provided with an end tongue 35 to fit slots 36 in the cross bar 9 and hold the fork positioned against movement in the discharging position shown in Figure 14. To bring about the discharging of the type from the fork 15 to the type holding channel a beveled plunger 37 is carried by a stem 38 slidably supported in the shoulder 39 on the other side of the fork head. The plunger passes through an opening 40 in a plate 41 vertically slidable in the end of 20 the fork head. The spring 42 surrounding the stem 38 normally holds the plunger pressed forwardly. A spring 43 surrounds the plate 41 between the fork head and the top of the plunger. The plate 41 projects through an opening 44 in the bottom wall of the type channel, as shown in Figure 10, so that in operation of the device the plate may be projected through the type channel, as indicated in dotted lines in Figure 10, to eject the type from the fork channel to the 30 bank channel.

With the fork placed in the position shown in Figure 14, the plunger will fit in behind the flange 12 upon the sorting frame and will be pushed back by its engagement with the frame 35 to compress the spring 42 and bring the tapered end of the plunger to the opening 40 through the plate 41, permitting the spring 43 around the plate to expand and push the plate 41 into the dotted line position shown in Figure 10, pushing the adjacent type out through the opening 34 in the fork head and into the upper end of the adjacent channel of the bank.

As will be understood, the fork will contain the particular size of type to be transferred to 45 the bank and in its discharging position be arranged in connection with the proper channel of the bank to receive that particular type. To save wear upon the type in the depositing operation the bottom of the sorting frame may be 50 fitted with a resilient insertion 45 and the under side of the top 23 of the frame and the adjacent rear portion of the supporting cross bar 11 similarly fitted.

In taking the type out from the lower ends 55 of the type channels the standard form of fork may be used in connection with the abutments at the lower end of the type channels in the usual manner.

Whereas the standard construction of bank 60 used for multigraph typesetters only accommodates the standard multigraph type, the present invention permits the sorting and depositing of multigraph printer's type of varying thicknesses, obviating the necessity of ordinary hand depositing, the bank itself being modified for the use of either multigraph type or multigraph printer's type.

While certain preferred embodiments of the invention have been shown, it is understood that 70 the same may be modified without departing from the principles of the invention as covered by the following claims.

I claim:

1. In an apparatus of the character described, 75

5 a type bank with type holding channels and a cross bar in connection with the inlet ends of the channels and formed with varying sizes of type passages registering with the inlet ends of the different channels.

10 2. In an apparatus of the character described, a type bank with type holding channels, a cross bar in connection with the inlet ends of the channels and formed with varying sizes of type passages registering with the inlet ends of the different channels, a cross bar in connection with the outlet ends of the channels and formed with corresponding discharge openings of varying size for the purpose set forth.

15 3. In an apparatus of the character described, a type bank with type holding channels, a cross bar formed with varying sizes of type passages registering with the inlet ends of the different channels and associated means for feeding type 20 of varying size to the varying sized openings of the cross bar, said feeding device including a releasing element actuatable by contact with the bank and cross bar to feed the type into said channels.

25 4. In an apparatus of the character described, a type bank with type holding channels, a cross bar in connection with the inlet ends of the channels and formed with varying sizes of type 25 passages registering with the inlet ends of the different channels, the cross bar embodying a wall overlapping said channels, and a connecting wall spaced apart from the ends of said channels

at varying degrees from the channel ends to form passageways of varying sizes connecting with different channels and associated means for feeding type of varying size through correspondingly sized passages to said channels.

5 5. In an apparatus of the character described, a type bank with type holding channels, a cross bar in connection with the inlet ends of the channels embodying a wall overlapping said channel ends at varying degrees from the channels 10 to form passageways of varying sizes for the different channels, associated means for feeding type of varying size through correspondingly sized passageways to said channels and said channels being formed at their discharge ends 15 with outlet openings of varying sizes corresponding with the varying sizes of the inlet openings for said channels.

6. In combination with a bank of a typesetting machine of the class described formed with 20 type holding channels, a cross bar in connection with the inlet ends of the channels and formed with a wall overlapping said channel ends and a connecting wall spaced apart from the channel ends at varying degrees from the channels to 25 form passageways of varying sizes for the different channels, associated means for feeding type of varying size through correspondingly sized passageways to said channels for separately discharging the type of varying sizes passing 30 through said channels.

CLARK S. STEVENS.
